UNITED STATES PATENT OFFICE.

CHARLES M. BUEBKE, OF PORTLAND, OREGON, ASSIGNOR TO PHILLIP F. BUEBKE, OF PORTLAND, OREGON.

DEMOUNTABLE BAGGAGE-RACK FOR AUTOMOBILE-RUNNING BOARDS.

1,393,200.

Specification of Letters Patent.

Patented Oct. 11, 1921.

Application filed September 26, 1919, Serial No. 326,662. Renewed August 10, 1921. Serial No. 491,292.

To all whom it may concern:

Be it known that I, CHARLES M. BUEBKE, a citizen of the United States, and a resident of Portland, county of Multnomah, and 5 State of Oregon, have invented a new and useful Improvement in Demountable Baggage-Racks for Automobile Running-Boards, of which the following is a specification.

In taking long trips, especially camping 10 trips, it is desirable to have a railing or rack provided on the running-board for holding baggage and other outfit. But since the rack would be in the way on other occasions, it must be demountable. It is also desirable 15 that the means for securing the racks on the running-board are without bolts or other devices requiring holes to be drilled in, or otherwise marring, the running-board.

With these objectives in mind, I invented 20 the device hereinafter illustrated in the accompanying drawings.

Incidentally I so contrived my rack that it is comparatively inexpensive to make, is strong, may be quickly and securely mounted 25 on the running-board, and as readily demounted.

In the accompanying drawings, Figure 1 is a perspective of my invention showing the same as secured to the running-board of an 30 automobile.

Fig. 2 shows a section of the running board of an automobile and illustrates the manner in which my rack is secured; and

Fig. 3 illustrates a detail of construction.

My invention consists of a metal frame *a*, 35 made of a flatiron or steel bar and formed with angular extremities, *a'*; the frame being substantially U-shaped and having laterally projecting integral clamping jaws *b*. On each of the ends *a'* of the frame is pivotally and slidably fastened a clamping member *c* and *c'*, also made with a laterally projecting companion jaw *d*. The pivotal and sliding connection of said clamping members

45 *c* and *c'* is effected through headed pins *e*, provided on the frame *a*, bearing in slots *f*, in the clamping arms. The upper ends of the clamping arms *c* and *c'* curve inward, that is, toward the middle of the rack. The 50 upper end of the clamping member *c* is pivotally fastened to a lever *g* which is pivoted at *h* to the frame *a*. The upper end of the clamping arm *c'* is pivotally connected to a lever-handle *j* which is pivoted to the frame

a at *i*. The lever-handle *j* is made with a 55 slot *k* in which bears a pin *l*, on the extremity of the lever *g*. The free end of the handle lever *j* is crooked as at *m*, to provide a finger-piece, and the lower end of said crooked portion is made with the laterally projecting 60 locking-rib *n*, for engaging with the underside of the lever *g*. The extremities of the clamping jaws *b*, are made with a biting rib, *o*; and on the inner surfaces of the companion jaws *d* of the slideable clamping members *c* and *c'*, are mounted rubber buttons *p*.

When my rack is to be attached to the running-board (Fig. 2), the slideable clamping members *c* and *c'*, are in the first instance lifted so as to increase the space 70 between their jaws *d* and the clamping jaws *b*, such spacing being effected by bearing down on the finger-piece *m*, thereby disengaging the locking rib *n* from the lever *g* and releasing the handle-lever *j*, which is 75 then lifted as shown in dotted outline in Fig. 1. The jaws *b*, *d*, of the frame and the clamping members may now be placed astride of the running-board, and by then forcing the lever handle *j* down, the biting 80 ribs of the jaws *b*, of the frame will bite into the underside of the running-board, and the rubber buttons *o* on the underside of the jaws *d* of the clamping members *c* and *c'* will grip firmly the upper side of the running-board, hence rigidly fastening my rack 85 in place.

The clamping jaws are locked together by bringing the locking rib *n* of the extremity of the lever-handle *j* against the 90 under edge of the lever *g*.

To demount my rack, all that is necessary to do is to disengage the extremity of the lever handle *j* from the lever *g*, then lifting the hand-lever so as to move the clamping jaws 95 *b*, *d*, apart, and in so doing, releasing the rack from the running-board.

I claim:

1. A device of the character described comprising a U-shaped frame provided with 100 a laterally projecting clamping jaw at each end, an adjustable clamping member carried by each end of the frame, such clamping member having a companion clamping jaw, levers pivoted to the ends of the frame and 105 adapted for arranging their free ends in alinement, the upper ends of said clamp members being pivoted to said levers, the

levers being operatively connected with each other, and means for locking the levers together after having been operated to place said clamping members in their clamping 5 position.

2. A device of the character described comprising a U-shaped frame provided with a laterally projecting clamping jaw at each end, an adjustable clamping member carried 10 by each end of the frame, such clamping member having a companion clamping jaw, levers pivoted to the ends of the frame and adapted for arranging their free ends in alinement, the upper ends of said clamp 15 members being pivoted to said levers, the levers being operatively connected with each other, one of said levers having a handle-like extension, and means for locking the levers together after having been operated to place 20 said clamping members in their clamping position.

3. A device of the character described comprising a U-shaped frame provided with a laterally projecting clamping jaw at each 25 end, an adjustable clamping member carried by each end of the frame, such clamping member having a companion clamping jaw, levers pivoted to the ends of the frame and adapted for arranging their free ends in 30 alinement, the upper ends of said clamp members being pivoted to said levers, the levers being operatively connected with each other, one of said levers having a handle-like extension, the free end of said handle 35 being provided with a locking-rib for engaging the other lever.

4. A device of the character described comprising a U-shaped frame provided with a laterally projecting clamping jaw at each 40 end, an adjustable clamping member carried by each end of the frame, such clamping member having a companion clamping jaw, levers pivoted to the ends of the frame and adapted for arranging their free ends in 45 alinement, the upper ends of said clamp members being pivoted to said levers, the levers being operatively connected with each other, one of said levers having a handle-like extension, the free end of said handle being 50 made with a crooked portion provided with a locking-rib for engaging the other lever.

5. A device of the character described comprising a U-shaped frame provided with a laterally projecting clamping jaw at each 55 end, a clamping member pivotally and slidably mounted on each end of the frame and having a laterally projecting companion clamping jaw, levers pivoted to the ends of the frame and adapted for arranging their 60 free ends in alinement, the upper ends of said clamping members being curved inward and pivoted to said levers respectively, the levers being operatively connected with each other, and means for locking the levers together 65 after having been operated to place

said clamping members in their clamping position.

6. A device of the character described comprising a U-shaped frame provided with a laterally projecting clamping jaw at each 70 end, a clamping member pivotally and slidably mounted on each end of the frame and having a laterally projecting companion clamping jaw, levers pivoted to the ends of the frame and adapted for arranging 75 their free ends in alinement, the upper ends of said clamping members being curved inward and pivoted to said levers respectively, the levers being operatively connected with each other, one of said levers having a handle-like extension, and means for locking the levers together after having been operated to place 80 said clamping members in their clamping position.

7. A device of the character described comprising a U-shaped frame provided with a laterally projecting clamping jaw at each end, a clamping member pivotally and slidably mounted on each end of the frame and having a laterally projecting companion 90 clamping jaw, levers pivoted to the ends of the frame and adapted for arranging their free ends in alinement, the upper ends of said clamping members being curved inward and pivoted to said levers respectively, the levers being operatively connected with each other, one of said levers having a handle-like extension, the free end of said handle being provided with a locking-rib for engaging 95 the other lever.

8. A device of the character described comprising a U-shaped frame provided with a laterally projecting clamping jaw at each end, a clamping member pivotally and slidably mounted on each end of the frame and having a laterally projecting companion clamping jaw, levers pivoted to the ends of the frame and adapted for arranging their free ends in alinement, the upper ends of 105 said clamping members being curved inward and pivoted to said levers respectively, the levers being operatively connected with each other, one of said levers having a handle-like extension, and means for locking the levers together after having been operated to 110 place said clamping members in their clamping position.

9. A device of the character described comprising a U-shaped frame provided with a laterally projecting clamping jaw at each 120 end, a clamping member pivotally and slidably mounted on each end of the frame and having a laterally projecting companion clamping jaw, levers pivoted to the ends of the frame and adapted for arranging their 125 free ends in alinement, the upper ends of said clamping members being curved inward and pivoted to said levers respectively, the levers being operatively connected with each other, one of said levers having a handle- 130

like extension, the free end of said handle being provided with a locking-rib for engaging the other lever.

10. A device of the character described comprising a U-shaped frame provided with a laterally projecting clamping jaw at each end, a clamping member pivotally and slidably mounted on each end of the frame and having a laterally projecting companion clamping jaw, levers pivoted to the ends of

the frame and adapted for arranging their free ends in alinement, the upper ends of said clamping members being curved inward and pivoted to said levers respectively the levers being operatively connected with each other, one of said levers having a handle-like extension, the free end of said handle being made with a crooked portion provided with a locking-rib for engaging the other lever. 15

CHARLES M. BUEBKE.
